(57) **CLAIM**

The ornamental design for a shower stand, as shown and described.

DESCRIPTION

FIG. 1 is a top perspective view of a shower stand, showing our new design;

FIG. 2 is a front elevational view thereof;

FIG. 3 is a rear elevational view thereof;

FIG. 4 is a right side elevational thereof, the left side elevational view being a mirror image thereof;

FIG. 5 is a top plan view thereof;

FIG. 6 is a top plan view thereof; and,

FIG. 7 is a bottom perspective view thereof.

The broken lines shown in the figures are for the purpose of illustrating portions of the shower stand that form no part of the claimed design.

1 Claim, 6 Drawing Sheets
